CALCULATING MACHINE

Anthony B. Machado, Oakland, Calif., assignor
to Friden Calculating Machine Co., Inc., a cor-
poration of California

Application October 21, 1940, Serial No. 362,021

9 Claims. (Cl. 235—63)

This invention relates to calculating machines and is concerned more particularly with the provision of improved means for resetting a register.

It is an object of the invention to provide an improved construction for effecting the return of the register to a predetermined or end position coupled with resetting of the register.

Another object of the invention is to provide a mechanism of the character referred to which is of a silent character.

Another object of the invention is to provide mechanism of the character referred to in which only a single cycle of the resetting mechanism is effected although the drive therefor may be enabled for one or more cycles of operation.

Other objects and advantages of the invention will be apparent from the following description of preferred embodiments in which:

Figure 1 is a longitudinal sectional view through the rear portion of a calculating machine embodying my invention;

Figure 2 is a fragmentary sectional view showing the front end of the section shown in Figure 1;

Figure 3 is a plan view partially in section with certain parts omitted and others shown schematically;

Figure 4 is a sectional side elevational view of the machine illustrating the shift and resetting control keys;

Figure 5 is a fragmentary detailed view showing the clutch construction;

Figure 6 is a fragmentary detailed view showing a part of the shifting control mechanism;

Figure 7 is a rear elevational view partly in section of the upper portion of the calculating machine;

Figure 8 is a fragmentary operational view;

Figure 9 is a fragmentary operational view.

The invention is disclosed as embodied in a calculating machine having actuating mechanism of the uni-directional, continuous drive cycle type wherein all power driven operations are effected by engagement and disengagement of a single clutch providing the only path of power from the motor of the machine. A calculating machine of this construction is disclosed in the copending application of Carl M. Friden, Ser. No. 42,268, filed September 26, 1935.

The frame of the machine may include a base 10 (Figure 1) upon which casing 11 is suitably mounted. Other frame parts include respective left and right side frame plates 12 and 13 which are suitably mounted in spaced-apart relation upon base 10. Side plates 12 and 13 may be con-

nected by various cross brackets 16, 17, 18 and 19 which serve various mechanism of the machine. The register carriage 22 is mounted on the frame brackets 16 and 19 by rollers 23 for endwise shifting movement laterally of the machine in either direction to various ordinal positions as controlled by means described hereinafter.

Carriage 22 includes a frame 31 in which 10 numeral wheels shafts 32 are journaled to carry numeral wheels 33 of conventional construction. To transmit increments of value to numeral wheels 33, each shaft 32 extends below the frame 31 and has a ten tooth gear 34 which is 15 actuated by means later described.

Accumulator resetting means

Means are provided on the carriage for resetting the numeral wheels 33 to zero registration 20 including means such as a rack bar 41 mounted for endwise sliding movement in the carriage frame adjacent the upper end of the numeral wheel shafts 32 for cooperation with mutilated gears 42 carried by numeral wheel shafts 32. 25 Adjacent gears 42 are axially offset to cooperate with the adjacent vertically offset racks found on rack bar 41 in the usual manner. The rack bar 41 is moved from its normal position to which it is spring urged in the usual manner to 30 engage gears 42 of any numeral wheel 33 displaced from the zero position and thereby reset the numeral wheels. Rack 41 may be operated manually in a conventional fashion or may be selectively connected to an actuating bar 46 35 mounted on the frame 31 for endwise movement by means of suitable mechanism as disclosed, for example, in the copending application of Carl M. Friden, Ser. No. 240,269, filed November 14, 1938.

Revolutions counter

The revolutions counter may comprise numeral wheels 51 on respective shafts 52 and may be actuated by means of the actuator 54 in the usual 45 manner. Counter numeral wheels 51 may be reset to zero by rack bar 53 similar to the rack bar 41 described above and also adapted for connection with the actuating bar 46 by suitable interponent means as disclosed in said application 240,269. The revolutions counter mechanism is conventional in all respects, and a further description is not believed necessary.

Selecting and actuating mechanisms

The values to be introduced into numeral

wheels 33 are selected by means of a plurality of banks or orders of settable value keys 61 (Figures 1 and 2). The keys 61 of each bank cooperate with selecting mechanisms including spring urged selecting slides 62 mounted for endwise movement to position gears 63 selectively with respect to the stepped teeth 64 of the associated actuating cylinder 66. Cylinders 66 (Figures 1 and 3) for adjacent orders are mounted on actuating shafts 67 having suitable bevel gear connections with a transverse drive shaft 68 which is suitably journaled in side plates 12 and 13. Shaft 68 and shafts 67 are driven cyclically from motor 69 through clutch 71 which may be driven by suitable gearing 72 (Figure 4) from the motor shaft 13. Clutch 71 (Figure 5) may be engaged or disengaged by oscillation of spring urged clutch pawl or dog 74 mounted for rotation with shaft 68, and with respect to ratchet 76 journaled on shaft 68 and driven by gearing 72. Clutch control lever 77 is pivoted on side plate 13 at 78 to determine engagement or disengagement of the clutch by releasing or engaging the nose of dog 74 in the full cycle position thereof.

The number of increments transmitted to the pair of gears 63 of an order by the associated cylinder 66 during cyclic operation of the clutch is transmitted to square shaft 81 on which gears 63 are mounted. Each shaft 81 extends rearwardly of the machine in the usual manner and carries a spool 82 having bevel gears 83 and 84 for cooperation with the aligned numeral wheel gears 34.

The selective engagement of gears 83 and 84 with gears 34 (Figure 1) is controlled by strap 85 positioned between the gears and mounted by suitable arms 86 for rocking movement with shaft 81. Thus, rocking of shaft 81 determines transmission of said increments to the numeral wheels 33 and also the direction of entering thereon. Any suitable control means may be provided for rocking the shaft 81 to control digitation operations. Shaft 81 may be centralized by opposed spring urged centralizing arms 91 cooperating with a central stop 92 and engaging a pin 93 carried by one of arms 86 on which the strap 85 is mounted.

Carriage shift mechanism

The carriage can be shifted in either direction by power driven means controlled by manually operable keys, and this mechanism is of conventional construction. Carriage 22 (Figure 7) is provided with toothed plate 101 along the rear side thereof for cooperation with shift pins 102 (Figure 7) on shift gear 103. Shift gear 103 can be rotated in either direction and receives one-half rotation for each rotation of clutch 71 referred to above. For this purpose, shift gear 103 is connected by reversing gearing to respective gear sleeves 106, 107 (Figures 3 and 7), the gearing being arranged so that when driven from gear sleeve 106 the rotation is in one direction, and when driven from gear sleeve 107 rotation is in the other direction. The respective gear sleeves 106, 107 (Figure 3) are slotted for engagement by toothed collars 108, 109 mounted on the rearward ends of a pair of adjacent actuating shafts 67. The collars 108 and 109 are provided with slidable driving connections 110 with the actuating shafts. The sliding movement of collars 108 and 109 is controlled by means of rods 111, 112 which extend forwardly of the machine.

Shift keys 113 and 114 (Figure 4) for operating the respective controlling rods 111 and 112 have respective pins 115 (Figure 6) for cooperation with respective levers 116 and 117. Lever 116 (Figures 3 and 6) is secured to transverse shaft 118 while lever 117 is secured to sleeve 119 mounted on shaft 118. Both shaft 118 and sleeve 119 are provided with respective depending arms 120 having their lower ends disposed in front of associated rods 111, 112 respectively, to determine operation thereof upon depression of the associated shift key.

To enable the drive by depression of the shift keys, the respective pins 115 (Figure 4) thereof 15 cooperate with cam slots in a pivoted lever 121 which is pivotally connected at its lower end to the upper end of lever 122 carrying an insulated pin 123 at its lower end. Pin 123 is adapted to close contacts 124 of the motor circuit upon depression of the shift key. Lever 121 is also connected by link 126 (Figures 4 and 5) with clutch control lever 77 so that such lever is rocked to clutch engaging position upon depression of a shift key.

25 From the foregoing, it is seen that the carriage can be shifted selectively in either direction by operation of keys 113 and 114.

Resetting drive and control mechanism

30 The means for effecting return and resetting of the registers may be effected by operation of key 131 (Figure 3) which operates to first effect return of the carriage to its leftmost position, and then to reset the registers. Upon depression 35 of key 131, it is latched in depressed position by a latch slide 132 mounted on side plate 13 for endwise movement. Slide 132 is urged to the left as viewed in Figure 4 by spring 133 connected to the pivot pin between slide 132 and its supporting and releasing bellcrank 134. The release 40 of latch 132 is referred to hereinafter.

Depression of key 131 serves to enable the shifting mechanism to cause shifting of the carriage to its leftmost position, to enable the resetting drive 45 connection for power resetting of the accumulator and the revolutions counter, as well as to enable the drive. Adjacent its lower end, key 131 is slotted to engage pin 136 on arm 137 (Figures 3 and 4) carried by a transverse shaft 138 50 journaled in side plates 12 and 13. Shaft 138 carries arm 141 (Figures 1 and 3) having a pivotal connection 142 with a forwardly extending pusher arm 143. Pivotal connection 142 is preferably made in the form of an adjustable eccentric to enable adjustment of pusher arm 143. Arm 143 is spring urged in a clockwise direction by a spring 144, so that notched end 146 thereof is in engagement with rod 147.

Rod 147 (Figure 3) is spring urged forwardly 60 by a spring 148 secured to a shifting fork 149 on rod 147 and engaging shiftable toothed collar 150 engageable with slotted hub 151 of a cam 152. Cam 152 (Figures 1 and 7) operates arm 153 which in turn operates actuating slide 154 for the resetting operation. Slide 154 cooperates with arm 156 secured on the actuating bar 46. Arm 156 is not lowered into engagement with the actuating slide therefor until the end of the shifting operation when the carriage is moving from the position shown in Figure 7 toward its leftmost position (to the right as viewed in Figure 7), because of pawl 158 cooperating with ledge 159 to maintain the arm 156 raised as the carriage is moving through its next to leftmost position as viewed from the front of the machine. Thus,

upon depression of the return and re-setting control key the resetting drive connection is enabled, but resetting cannot occur unless the carriage is in its leftmost position or until it is returned to such position if displaced therefrom, as later described. While the drive for the resetting cam is effective, arm 156 is maintained inactive until the last cycle of operation when the carriage is in its leftmost position.

To enable return of the carriage, pusher arm 143 (Figures 1 and 3) carries pin 161 which is cooperatively related to depending arm 162 which is secured on shaft 118. Thus, upon rearward movement of pusher arm 143, arm 162, shaft 118, and arm 120 thereon are rocked to shift rod 111 rearwardly and thereby engage the left hand shift mechanism.

To enable the drive upon depression of the return clear key 131, roller 166 thereon (Figures 4 and 5) is adapted to engage cam edge 167 of clutch control lever 71 to rock the lever to clutch engaging position. Lever 71 when rocked to clutch engaging position also operates through link 126 and levers 121 and 122 to close contacts 124.

In order to prevent more than one operation of the resetting means at the end of the shifting operation, yieldable over-ride pawl 171 (Figure 7) which cooperates with shift gear 103 in the leftmost position of the carriage to prevent attempted shifting beyond such position has an extension 172 overlying a slide 173 (Figures 3 and 7) mounted on the bracket 19 for vertical movement. Slide 173 when moved downwardly engages one arm 174 (Figure 4) of a bellcrank having a depending arm 175 connected by a link 176, with arm 177 depending from a cross shaft 178. Cross shaft 178 (Figures 1 and 3) carries an arm 179 having a notched laterally offset end 180 which underlies arm 143. Thus, during a cycle of the machine in which the resetting operation is effected, arm 179 will be operated to lift arm 143 out of engagement with rod 147, so that the rod 147 is restored to its inactive position to disconnect the drive means. Also the lifting movement of arm 143 (Figure 1) lifts pin 161 out of engagement with arm 162 to disable the control linkage of the left hand shift mechanism. Thus, even though the return-clear key be maintained depressed, only one cycle of resetting operation can occur. The mechanism described above is of the character disclosed in said Friden application Serial No. 240,269.

As seen in Figure 7, spring 181 which urges arm 153 against cam 152 is secured at one end to pin 182 on arm 153 which upon oscillation of the arm 153 to its extreme position by cam 152, is adapted for engagement with notched end 183 of latch arm 184 pivoted at 186 on bracket 187 in which the cam 152 is also journaled. Latch arm 184 is urged in a clockwise direction by spring 188 so that upon oscillation of arm 153 by cam 152 upon initial depression of the return clear key, notched end 183 will engage pin 182 to prevent further oscillation of the arm 153 until the carriage reaches its end position.

During the return of the carriage to its end position, means is brought into play to disable the latch arm 184 so that the cam follower arm 153 which operates the resetting mechanism from the cam 152 is again free to follow the cam. For this purpose the carriage shift rack 101 carries a roller 191 which is adapted for engagement with cam extension 192 of the arm 184 as the carriage is entering its left-most position. This con-

dition of the parts is shown in Figure 8 where the cam follower arm 153 is latched in displaced position by the latch lever 184 and the roller 191 is just beginning its engagement with the cam extension 192 of the latch lever. Preferably the timing of the parts is such that the release of the cam follower arm 153 from its latch occurs just as the high point of the cam 152 is in position to engage the roller on the cam follower lever as shown in Figure 9, so that there is no appreciable impact or noise accompanying the release of such lever. After its release, cam 153 during its next rotation oscillates the arm 153 and operates the slides 154 and 46 to perform the resetting operation.

During the resetting cycle the key 131 is released by the operation of bell crank 134 by the extension 172 of pawl 171 so that latch 132 is withdrawn.

I claim:

1. In a calculating machine having a shiftable register and return and resetting mechanism therefor, said mechanism being operable to return said register to a predetermined position if displaced therefrom and to effect resetting of said register, drive means, said mechanism including a resetting cam having a drive connection with said drive means, an arm oscillated by said cam, a latch for holding said arm out of cooperation with said cam, a spring urging said latch to active position, and means responsive to said register when it is returned to said predetermined position for disabling said latch.
2. In a calculating machine having a shiftable register and return and resetting mechanism therefor, said mechanism being operable to return said register to a predetermined position if displaced therefrom and to effect resetting of said register, drive means, said mechanism including a resetting cam having a drive connection with said drive means, an arm oscillated by said cam, a latch for holding said arm out of cooperation with said cam, a spring urging said latch to active position, and means responsive to said register when it is returned to said predetermined position for disabling said latch, said last named means including an element shiftable with said register and engageable with said latch to effect disabling thereof.
3. In a calculating machine having a shiftable register and return and resetting mechanism therefor, said mechanism being operable to return said register to a predetermined position if displaced therefrom and to effect resetting of said register, drive means, said mechanism including a resetting cam having a drive connection with said drive means, an arm oscillated by said cam, a latch for holding said arm out of cooperation with said cam, a spring urging said latch to active position, and means responsive to said register when it is returned to said predetermined position for disabling said latch, said last named means including an element shiftable with said register and engageable with said latch to effect disabling thereof.
4. In a calculating machine having a shiftable register and return and resetting mechanism therefor, said mechanism being operable to return said register in step-by-step fashion to a predetermined position if displaced therefrom and to effect resetting of said register, drive

means being cooperatively related and arranged so that disabling of the latch is effected while said arm is cooperatively related to the high portion of said cam.

means for said mechanism, said mechanism including a resetting cam having a drive connection with said drive means, an arm oscillated by said cam between an inward position and an outward position, latch means for automatically engaging said arm upon movement thereof by said cam from said inward to said outward position to hold said arm in said outward position, and latch releasing means operable in timed relation to the rotation of said cam and during the last step of return movement of said register for disabling said latch means with said cam in a position corresponding to the outward position of said arm whereby said arm is restored into operative relation with said cam for the resetting portion of the return and resetting operation.

5. In a calculating machine having a shiftable register and cyclically operable return and resetting mechanism therefor, said mechanism being operable to return said register to a predetermined position if displaced therefrom and to effect resetting of said register during a resetting cycle of operation of said mechanism, drive means, a resetting cam having a drive connection with said drive means, an arm oscillated by said cam between an inward position and an outward position, latch means for automatically engaging said arm upon movement thereof by said cam from said inward to said outward position to hold said arm in said outward position, latch releasing means operable in timed relation to the rotation of said cam for disabling said latch means with said cam in a position corresponding to the outward position of said arm, and means for operating said releasing means during the last cycle of operation prior to the resetting cycle.

6. In a calculating machine having a shiftable register and return and resetting mechanism therefor, said mechanism being operable to return said register to a predetermined position if displaced therefrom and to effect resetting of said register, drive means, a resetting cam having a drive connection with said drive means, an arm oscillated by said cam between an inward position and an outward position, latch means for automatically engaging said arm upon movement thereof by said cam from said inward to

said outward position to hold said arm in said outward position, and latch releasing means operable in timed relation to the rotation of said cam for disabling said latch means with said cam in a position corresponding to the outward position of said arm, said releasing means serving to hold said latch means inactive when said carriage is in said predetermined position.

7. In a calculating machine having a shiftable carriage, a register in said carriage, means for resetting said register including a cam and a cam follower, drive means for said resetting means, control means for enabling said drive means with respect to said resetting means, and automatically operable means brought into play by movement of said cam follower by said cam for holding said cam follower in an inactive position with reference to said cam.

8. In a calculating machine having a shiftable carriage, a register in said carriage, means for shifting said carriage, means for resetting said register including a cam and a cam follower, common drive means for said shifting and resetting means, control means for simultaneously enabling said drive means with respect to said shifting and resetting means, automatically operable means brought into play by movement of said cam follower by said cam for holding said cam follower in an inactive position with reference to said cam, and means on said carriage for disabling said holding means.

9. In a calculating machine having a shiftable carriage, a register in said carriage, means for shifting said carriage, means for resetting said register, said resetting means including a cyclically operable drive train having a rotating portion and a reciprocating portion, means for initiating a plural cycle operation of said drive train, and means cooperatively related to said reciprocating portion and brought into play upon initial movement of said reciprocating portion by said rotating portion for maintaining said reciprocating portion inactive until near the end of the plural cycle operation, said rotating portion being maintained active throughout said plural cycle operation.

ANTHONY B. MACHADO.
